UNITED STATES PATENT OFFICE.

CHARLES RENARD AND ALBERT RENARD, OF NONANCOURT, FRANCE.

PILE-THREAD-DISTRIBUTING BLADE FOR LOOMS.

1,163,109.

Specification of Letters Patent.

Patented Dec. 7, 1915.

Application filed January 28, 1914. Serial No. 815,082.

To all whom it may concern:

Be it known that we, CHARLES RENARD and ALBERT RENARD, citizens of the Republic of France, residing in Nonancourt, Eure, France, have invented certain new and useful Improvements in Pile-Thread-Distributing Blades for Looms, of which the following is a specification.

This invention comprises improvements in the power loom for the mechanical manufacture of Oriental, wound and other knot-stitch carpets, forming the subject of our United States Patent No. 894,287, of 28th July 1908 and of the application Serial 15 606,143 of 2nd February 1911 and it relates to guide-blades for distributing apparatus which bring the pile thread from the bobbins to the distributing center, where it is seized by nippers which present it to the 20 looping tool. Heretofore, in these guide-blades as well as in all other known systems of distributers, the retention of the thread is effected either by means of a spring acting directly by pressure and by force upon the 25 said thread, or by means of small pieces or levers interposed between the spring and the thread, but with these arrangements there are the following objections. 1. The pressure of the interposed lever or spring, calculated for the normal delivery of the pile 30 thread has no useful effect owing to the more or less great resistance and other causes (inherent to the unwinding of the bobbins), as through the force of the resistance and of 35 the elasticity of the thread, there is produced immediately after the cutting of the pile thread a backward slip of the said thread causing it to be dragged from the guide-blade or the length of its outward projection 40 to be simply decreased whereby the distributing nipper is prevented from seizing it. 2. In order to remedy this defect, it is necessary to increase the force of the spring in order to more effectually retain the pile 45 thread, but then this retention becomes too great for the proper working of the distributing nipper; there is a stretching or deformation of the pile thread, and its dragging or breakage becomes inevitable every time that an enlargement, an impurity, or 50 a knot is met with in the thread, the resistance of which can no longer overcome the excess of power of the spring.

In knot-stitch looms wherein many hundreds and even thousands of distributers and

bobbins may be employed in a single loom, it is absolutely necessary to avoid all these objections, which this has not yet been the case with any system, and it is with this object that our improvements have been devised.

Our invention consists in the adaptation of a small steel blade placed nearly or exactly perpendicular to the pile thread. This blade which, practically, offers no resistance to the delivery of the pile thread, blocks the latter against any backward or return movement by binding or wedging, preventing its being dragged and thus always insuring the same length of projection outside the blade to be seized by the distributing nipper, which condition is of the greatest importance. On the other hand, this arrangement placed in a direction perpendicular to the pile thread, and in the axis of the guide blade, considerably diminishes its encumbrance, allows of employing a distributer of very slight thickness and consequently facilitates the multiplicity of apparatus in the width of the loom.

The following description with reference to the accompanying drawing will enable the peculiarities and advantages of our invention to be fully understood.

In said drawings: Figure 1 shows a side elevation of a guide embodying the invention. Fig. 2 is a front elevation of the same. Figs. 3 and 4 are vertical sectional views, Fig. 4 showing a thread passing through the guide. Figs. 5, 6, 7 and 8 are views similar to Figs. 1, 2, 3 and 4, showing a guide for a plurality of threads. Figs. 9, 10 and 11 illustrate modifications of the guide, the figures being vertical sectional views.

The guide-blade 1 of the distributer (shown in side elevation at Fig. 1) is adapted at its upper part, to slide in the grooves arranged on the distributer and to work under the action of the Jacquard for the presentation of the pile thread of the distributing nipper, and at its lower part it is provided with a thin sheet metal sheath 2 bent into a U-shape and fixed by rivets 3, 4 forming a conduit 5 for the thread, (see the front view Fig. 2 and the sections on the line A B, Figs. 3 and 4). At its base, the guide-blade is, besides, rounded on the inlet side for the thread in order to facilitate the passage of the latter, and it is notched on the opposite side in order to allow of placing perpendicularly or nearly so with relation to the inner

wall 6 of the conduit 5, a small steel strip or blade 7 forming a spring let into and riveted in, the guide-blade at its upper end. The free end of the strip 7 is separated from the wall 6 by a small space which in certain cases may become *nil*. This distance is determined by the size of the thread to be distributed.

With a guide-blade thus constructed when 10 the pile thread 8, is drawn by the distributing nipper in the direction indicated by the arrow (Fig. 4), the small steel strip or blade moves slightly outward and practically offers no resistance to the passage of the pile 15 thread; if on the contrary, the pile thread is drawn in the other direction, the small strip or blade immediately tends to resume its natural position, acts with its end and effectually blocks the pile thread by binding 20 or wedging, thus serving a double purpose, namely, facilitating the passage of the pile thread and rendering it impossible for the latter to move back. The end 9 of the guide blade serves as a recoil stop for the small 25 steel strip in case of requirement. This arrangement is applicable for obtaining multiple 30 distribution guide-blades.

Figs. 5, 6, 7 and 8 are respectively a side elevation, a front elevation, and sections 35 through the line C D, Fig. 6, of a multiple distribution guide-blade of this kind.

On a guide-blade 10 is fixed by rivets 11, 12, 13, a sheath 14 which forms two conduits 15, 16 (it might form more if required) by the interposition of the partition 17 fixed between the two lateral walls of the sheath 14 by the rivets 18, 19. In each of these two conduits 15 and 16 is arranged and fixed, as before, in the guide blade, a 40 small strip or blade 20 which operates like the strip of the first arrangement. The rivets 21 serve to direct the thread 8, while the rivets 22 form recoil stops for the small steel strips in case of requirement. The arrangement of the small steel strips in a perpendicular or slightly oblique direction with 45 relation to the thread, their length, their thickness and their width vary according to the size of the pile thread, and the conduits 50 are also made according to this size, so that not only can the threads pass but also the knots which they contain.

The following modifications may also be adopted without departing from the principle of the invention: In the first modification (Fig. 9) a small rigid piece 25 which can freely oscillate is arranged in place of the small steel strip or blade; in the second (Fig. 10) this piece is subjected to the action 55 of a tongue or spring 26 which has solely for object to bring it back into the vertical position; in the third and last modification, two small steel strips or blades 23 and 24 (Fig. 11) are arranged one behind 60 the other in the same conduit; instead of

two strips, there may be more, and further these strips may be replaced by the rigid pieces shown in Figs. 9 and 10.

What we claim is:

1. A distributing guide-blade for threads 70 of looms, having a surface over which the thread is adapted to run, and a strip on said guide, said strip being of a length slightly less than the perpendicular distance between its point of attachment and the surface 75 over which the thread runs, said strip being adapted to yield in one direction and permit the running of the thread and adapted to resume a position approximating a perpendicular to said surface over which 80 the thread runs and wedge the thread between the end of said strip and said surface to prevent the backward running of the thread.

2. A distributing guide-blade for threads 85 of looms, having a surface over which the thread is adapted to run, and a spring-strip on said guide, said strip being of a length slightly less than the perpendicular distance between its point of attachment and the surface 90 over which the thread runs, said strip being adapted to yield in one direction and permit the running of the thread and adapted to resume a position approximating a perpendicular to said surface over which the 95 thread runs and wedge the thread between the end of said strip and said surface to prevent the backward running of the thread.

3. A distributing guide-blade for threads 100 of looms, having a surface over which the thread is adapted to run, and a strip on said guide, said strip being of a length slightly less than the perpendicular distance between its point of attachment and the surface over 105 which the thread runs, said strip being adapted to yield in one direction and permit the running of the thread and adapted to resume a position approximating a perpendicular to said surface over which the thread runs and wedge the thread between 110 the end of said strip and said surface to prevent the backward running of the thread, and a stop for preventing said strip moving backward beyond the perpendicular.

4. A distributing guide-blade for threads 115 of looms, having a surface over which the thread is adapted to run, and a spring-strip on said guide, said strip being of a length slightly less than the perpendicular distance between its point of attachment and the surface 120 over which the thread runs, said strip being adapted to yield in one direction and permit the running of the thread and adapted to resume a position approximating a perpendicular to said surface over which 125 the thread runs and wedge the thread between the end of said strip and said surface to prevent the backward running of the thread, and a stop for preventing said strip moving backward beyond the perpendicular. 130

5. A distributing guide-blade for threads of looms, having a plurality of surfaces over which the threads are adapted to run, said surfaces being located one above another, and a plurality of strips on said guide, said strips each being of a length slightly less than the perpendicular distance between its point of attachment and the surface over which the thread runs, said strips 10 being adapted to yield in one direction to permit the running of the threads and adapted to resume positions approximating a perpendicular to said surfaces over which the threads run and wedge the threads between the ends of said strips and said surfaces to prevent backward running of the threads.

6. A distributing guide-blade for threads of looms, having a surface over which the 20 thread is adapted to run, and a plurality of strips on said guide, said strips acting in conjunction with one surface and each being

of a length slightly less than the perpendicular distance between its point of attachment and the surface over which the thread runs, said strips being adapted to yield in one direction to permit the running of the thread and adapted to resume positions approximating a perpendicular to said surface over which the thread runs and wedge the thread between the ends of said strips and said surface to prevent backward running of the thread.

In witness whereof we have hereunto signed our names in the presence of two 25 sub-scribing witnesses.
